UNITED STATES PATENT OFFICE.

FREDERICK WINK, OF PHILADELPHIA, PENNSYLVANIA, ASSIGNOR TO
THOMAS DOLAN, OF SAME PLACE.

DESIGN FOR SHAWL-PATTERN.

Specification forming part of Design No. 6,079, dated August 20, 1872.

Specification describing a Design for a Shawl-Pattern, invented by FREDERICK WINK, of Philadelphia, Pennsylvania.

Design for a Shawl-Pattern.

The figure in the accompanying drawing represents sufficient of a shawl-pattern to illustrate my design, which consists of the two stripes A and B. The latter are precisely alike on both sides of their center lines *x* and *y*, and it has not been deemed necessary, therefore, to illustrate the whole width of the same.

Both stripes consist of a series of minor parallel stripes or ribs of varying width and of different shades or colors. The stripe A has a central rib, *a*, ornamented by diamond-

shaped spots and angular figures, as shown; and the stripe B has a rib, *b*, similar to the rib *a*, at each side of its central rib *d*, the latter having ornaments of a character too clearly shown in the drawing to need description.

Irrespective of the colors employed, I claim—

The design for a shawl-pattern, substantially as described, and as illustrated in and by the accompanying drawing.

In testimony whereof I have signed my name to this specification in the presence of two subscribing witnesses.

FRED. WINK.
